Patented Nov. 5, 1918.

UNITED STATES PATENT OFFICE.

WILLIAM H. BENNETT, OF VICTORIA, BRITISH COLUMBIA, CANADA.

HAT-BLOCK.

1,283,637.

Specification of Letters Patent.

Patented Nov. 5, 1918.

Application filed February 15, 1918. Serial No. 217,419.

To all whom it may concern:

Be it known that I, WILLIAM H. BENNETT, a citizen of the Dominion of Canada, residing at Victoria, in the Province of 5 British Columbia, Canada, have invented certain new and useful Improvements in Hat-Blocks, of which the following is a specification.

This invention relates to a hat block such 10 as is used for forming and working a felt hat on, and to the rest block or "spinner" on which the same is rotatably supported. These blocks are usually made of hardwood and in such material are subject to several 15 objections beyond their cost. Their bulk being considerable, unless very carefully seasoned, they are subject to warpage and splitting. Further, as they cannot be hollowed out in any great extent without rendering them more liable to warp and split, the cavity surrounding the central manipulating handle is usually too small to afford a convenient hold, and the weight of the heavy block is fatiguing to the operator.

20 These objections are overcome in the construction, which is the subject of this application, by forming the block as a thin shell molded in a plastic material which hardens on setting into a strong non-absorbent structure, and by providing a sufficient handle within the ample hollow of the block and connected to the crown thereof, thus providing a light, strong hat block which is easily manipulated and which is not subject 25 to sensible variation under atmospheric changes.

Instead of supporting this hollow hat block on the rest block in the usual manner with a central pivot, the rest block is 30 constructed of similar material to the hat block and has a circular projection which fits the circular mouth of the hollow of the hat block, so that it may be freely and steadily rotated on the rest block.

35 The rim block and its support are similarly constructed to have the same advantages of lightness and strength.

The invention is fully described in the following specification, reference being made 40 to the drawing herewith, in which:

Figure 1 shows the hat block in vertical section.

Fig. 2 is a similar view of the rest block or support for the same.

Fig. 2^a is a detail horizontal section on 55 the line 2^a—2^a on Fig. 2.

Fig. 3 is an inverted plan showing the underside of the hat block.

Fig. 3^a is a detail vertical section on the line 3^a—3^a on Fig. 3.

In the drawings herewith 2 represents the body of the hat block which is molded to the required size and form of a plastic cement composed of a fibrous material mixed with Portland cement or the like and water. It 65 is molded with an ample cavity or hollow 3, and on a metal base ring 4, preferably of non-corrodible thin sheet metal, having an inner and an outer upwardly turned flange 5 to protect the corners. This base 70 ring 4 is effectively keyed to the cement by projections 6 which may be either pins secured in and upwardly projecting from the base ring, or if, as preferred, of thin sheet metal, these upwardly projecting key portions may be sheared and upwardly turned from the base ring, as shown in the drawing.

The central handle 7 is molded of the same fibrous cement on a stem 8 of twisted 80 wire strands, the ends of which are spread apart, as at 9, to obtain an effective hold of the cement in the handle 7, and at the other end are bent, as shown at 10, and embedded in the cement of the hat block 85 body.

The rest block 11 is circular in form and hollowed as shown, with a metal ring 12 formed with a circular projection to fit the circular aperture of the hat block base 90 ring 4.

Inwardly projecting from the mouth ring 12 of the rest block is a lip 13 to facilitate handling, and the metal ring 12 has projections 14 stamped and inwardly bent from 95 it to afford a securing hold in the cement and to reinforce the lip 13.

The block on which the rim of the hat is worked, and its rest block, not illustrated, are made of the same fibrous cement, the 100 latter being hollow for lightness and to facilitate handling, and the edges of both, where exposed to wear, are protected with light metal rings, as in the case of the hat block and its rest block.

105 By this construction cheap, serviceable and convenient hat and rim blocks are substituted for the expensive and unhandy

wooden blocks at present used in hat manufacture and provide a steadier base for rotation.

Having now particularly described my invention, I hereby declare that what I claim as new and desire to be protected in by Letters Patent, is:

1. A hat block and its supporting rest block each composed of a relatively thin 10 wall of a fibrous cement composition, the hat block springing from a metal base ring having a circular aperture communicating with the cavity of the hat block and having provision for bonding it to the fibrous cement 15 composition of the wall, said hat block having a central handle with a metal stem expanded in the handle at one end and in the wall of the hat block at the other, the rest block having a projection fitting the aperture of the base ring of the hat block.

2. A hat block and its supporting rest block, each composed of a relatively thin 20 wall of a fibrous cement composition, the hat block springing from a metal base ring having a circular aperture communicating with the cavity of the hat block, the edges of the 25 base ring being upwardly turned to protect the corners and having provision for bonding it to the fibrous cement composition of the wall, said hat block having a central handle with a stem composed of wires which are outwardly bent and embedded in the 30 cement of the wall, the rest block having a projection fitting the aperture of the base 35 ring of the hat block.

3. A hat block and its supporting rest block, each composed of a relatively thin 40 wall of a fibrous cement composition, the hat block springing from a metal base ring having a circular aperture communicating with the cavity of the hat block, the edges of the 45 base ring being upwardly turned to protect the corners and having provision for bonding it to the fibrous cement composition of the wall, said hat block having a central handle with a stem composed of wires which are outwardly bent and embedded in the cement of the wall, the rest block having a shouldered metal projection fitting the aperture

ture of the base ring of the hat block with 50 provision for bonding it to the wall of the rest block.

4. A hat block and its supporting rest block, each composed of a fibrous cement composition enabling them to be hollowed 55 out to a relatively thin wall, the hat block built upon an oval metal base ring having a circular aperture communicating with the cavity of the hat block, the edges of the base ring being turned upward to protect the corners and having provision for bonding it to the composition of the walls, said hat block having a central handle within the cavity of the same composition with a stem composed of wires the upper ends of which are outwardly bent and embedded in the composition 60 of the walls, the rest block having a shouldered circular projection fitting the circular aperture of the base ring of the hat block, the shouldered projection having an 65 external ring of metal to protect the corners with provision for bonding it to the composition.

5. A hat block and its supporting rest block, each composed of a relatively thin 75 wall of a fibrous cement composition, the hat block built upon a metal base ring having a circular aperture communicating with the cavity of the hat block, the edges of the base ring being upwardly turned to protect 80 the corners and having provision for bonding it to the fibrous cement composition of the walls, said hat block having a central handle of the same composition with a stem composed of twisted wires the upper ends 85 of which are outwardly bent and embedded in the composition of the walls, the rest block having a shouldered circular projection fitting the circular aperture of the base 90 ring of the hat block, the shouldered projection having an external ring of metal to protect the corners with provision for bonding it to the cement and an inwardly projecting lip surrounding the aperture communicating with the cavity to facilitate 95 handling.

In testimony whereof I affix my signature.
WILLIAM H. BENNETT.
